(57) **CLAIM**

The ornamental design for flexible bag support, as shown and described.

DESCRIPTION

FIG. 1 is an isometric view of design for flexible bag holder with a flexible bag shown in dashed outline supported thereon that constitutes no part of the design.

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a back view thereof.

The cross hatching shading in FIGS. 1-3, 6 and 7 is fragmentarily shown for purposes of illustration, it being understood that the cross hatching shading is uniformly continued over the surface on which it appears.
